John J. Kelly

UNITED STATES PATENT OFFICE

MANUEL HERRERA DE HORA, OF NEW YORK, N. Y.

AIRCRAFT

Application filed October 17, 1928. Serial No. 313,145.

This invention relates to improvements in aircraft in general and to flying boats in particular.

The primary object of the invention resides in a flying boat which possesses great stability to safely "take off" or "land" in rough or choppy water without fear of accidentally upsetting and endangering the lives of those persons aboard the craft.

Another object of the invention is to provide a flying boat having a buoyant hull provided with a double keel to facilitate landing upon either ice or water, and a pocket in the underside of the hull intermediate the respective keels which is formed with a restricted throat at the front which gradually increases in width to terminate in a rear open mouth, which pocket tends to ease the hull from the surface of a body of water when the necessary forward speed is maintained as the head resistance upon the hull is materially reduced.

Another object is the provision of a flying boat having a double keel with parallel weighted skis extending the length thereof and being disposed on opposite sides of the vertical center of buoyancy of the hull whereby any lateral tilting or rocking of the hull will accordingly change the metacenter which will enable the hull to quickly right itself to its proper equilibrium.

A further object is to provide a hull for a flying boat or seaplane, which is provided with a stepped under bottom running fore and aft which lessens the draft of the rear of the hull and reduces the resistance when moving over a body of water.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a front elevation of my improved flying boat.

Figure 2 is a side elevation thereof.

Figure 3 is a bottom plan view.

Figure 4 is a vertical transverse sectional view on the line 4—4 of Figure 2.

Figure 5 is an enlarged vertical longitudinal section view.

Figure 6 is an enlarged detail vertical transverse sectional view on the line 6—6 of Figure 2.

Figure 7 is a front elevation showing the aircraft in a slightly tilted position in dotted lines.

Referring to the drawings by reference characters, the numeral 10 designates my improved flying boat in its entirety which includes a buoyant hull 11 embodying a plurality of air pockets or pontoons 12 above which the cabin and deck superstructure 13 rises. The usual wings 14 extend from opposite sides of the superstructure while motors 15 are mounted thereon on the center of buoyancy of the craft and at equal distance on opposite sides thereof to give equilibrium thereto.

The bow of the hull 11 is pointed as shown in Figures 1 to 3 inclusive and is stream line throughout its length terminating in a narrow stern where the usual vertical rudder 16 and elevators or stabilizers 17 are mounted. The underside of the hull curves forwardly and upwardly to the prow as at 18 and has two transverse steps 19 and 20 which reduces the draft of the hull throughout its length and greatly reduces the resistance during travel of the hull through the water which enables the craft to quickly rise when "taking off".

The front under bottom of the hull is provided with a transversely concaved pocket 20' which terminates at the bow below the water line in a restricted throat 21 which gradually increases to an enlarged open mouth 22 which terminates at the step 19. The peculiar shape of the pocket also acts to reduce resistance of the hull through the water and aids in effecting quick rise of the craft in "taking off".

The front under bottom of the hull is provided with spaced parallel runners or skis 23 which are in reality railroad rails as shown in Figure 6 of the drawing wherein the base flanges are bolted or otherwise se-

cured to the hull with the heads of the rails acting as the tread surface. The runners constitute a double keel and are shaped to conform to the front upward curve of the hull, however, they terminate short of the pointed prow but extend rearwardly to the step 19 and the rear ends thereof are upturned as shown in Figure 5. The runners are quite heavy and are disposed evenly on opposite sides of the center of equilibrium of the hull to properly balance the same and give thereto a low center of gravity.

Mounted beneath the hull rearward of the step 20 are landing sprags 24 to support and protect the tail end of the hull from dragging upon a supporting surface, while at the extreme rear end, the hull is formed with a tunnel or pocket 25 in which a propeller 26 is disposed. The propeller is driven by an auxiliary motor 27 by which the craft may be driven through the water in the event that the engines 15 should become disabled. A ship's steering rudder 28 is mounted rearward of the propeller 26 and is operatively connected with the aircraft rudder 16 and is controlled by the same steering mechanism.

In practice, the hull of the aircraft floats on an even keel as best seen in full lines in Figures 1, 4 and 7 of the drawings and any lateral rocking of the hull caused by the same moving over a rough body of water during "taking off" or "landing" of the aircraft will accordingly change the metacenter as seen in dotted lines in Figure 7, wherein one of the keels is disposed below the horizontal level of the other. However, the hull will quickly right itself to bring itself back to proper equilibrium, thus preventing the accidental capsizing of the same. Although, I have described the hull as that for a seaplane it may also "take-off" and "land" on ice or snow at which time the keels act as runners or skis.

From the foregoing description, it will be seen that I have shown and described a stable aircraft for "taking off" and "landing" on water, snow and ice, and wherein the underside of the hull is so constructed as to materially reduce resistance and aid in quickly rising into the air.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. In an aircraft, a buoyant hull having a bottom stepped transversely at intervals and being upturned in curved formation to the bow of the craft, said bottom having a ta-

pered pocket formed therein and extending from the bow to the first step thereof, said pocket being transversely curved and terminating at its forward end in a restricted throat and at its rear end in an open mouth.

2. In an aircraft, a buoyant hull having a pocket formed in the forward portion of its bottom and being curved upwardly toward the bow of the craft, runners secured to the bottom upon opposite sides of the pocket and following the longitudinal curvature of the bottom, said runners being in the form of inverted rails, base flanges formed with said rails and secured to the bottom and heads included in said rails and providing tread surfaces, and said runners terminating at their forward ends rearwardly of the bow and having their rear ends upturned and terminating beyond the rear end of said portion of said bottom.

In testimony whereof I have affixed my signature.
